CONTROLLING DEVICE FOR ENGINES

Julius Kuttner, Long Island City, N. Y., assignor
to Omo Aktiengesellschaft, Zurich, Switzerland

Application May 4, 1932, Serial No. 609,245

8 Claims. (Cl. 123—140)

My invention relates to controlling devices for internal combustion engines and more particularly to governors for engines in which hydrocarbon fuel is fed by a fuel pump.

In governors in use at the present time, it is customary to control separately either the quantity of fuel or the timing automatically. In controlling the amount of fuel to be fed, it is usual to provide a fixed stop which limits the movement of the control rod so that no more fuel can be fed to the engine than it can burn cleanly at the least favorable engine speed. Such a construction is unsatisfactory as at high speeds the engine can burn completely more fuel than can be fed to it because of the stop.

According to my invention, I provide a single governor driven by the engine which controls the quantity of fuel fed by the pump, that is, the length of time during which fuel is fed, and, by a separate mechanism, the timing or the moment during the engine cycle when the feed of fuel begins. In other words, a single device both controls the power of the engine and preserves the proper timing.

The principal object of my invention is to provide a construction in which a single governor controls independently both the feed of fuel and the timing of an engine.

A second object is to produce a device of this type which includes means to prevent stalling of the engine.

A further object is to vary the limiting action of a stop device so that at any speed the feed of fuel cannot be so great as to supply more fuel than the engine can burn cleanly.

Another object is to provide means to prevent too great speed, such means being controlled by the same governor.

An additional object of the invention is to devise a governor which is sensitive at low speeds.

Still another object is to produce a simple and sturdy arrangement for accomplishing the above results.

The final object is to make the control of an engine simple and effective at all speeds.

Other objects and advantages of the invention will appear more fully from the following description when taken in conjunction with the accompanying drawings which form a part thereof.

In the drawings:

Fig. 1 is a cross section through a governor device embodying my invention taken longitudinally of the engine shaft this view showing the

parts in the position they will assume when the engine is running.

Fig. 2 is a cross section taken transversely of the said shaft with the engine stationary.

Fig. 3 is a side elevation showing a modified form of the invention.

The governor is driven by an extension 4 of the auxiliary shaft 2 driven by the engine. A gear 6 on the shaft extension 4 engages a gear 8 on the vertical shaft 10 mounted in bearings 12, 14 in the governor casing 16. A frame 18 is fixed on the upper end of the shaft 10. Governor weights 20 are pivotally mounted as at 22 on the frame 18 so as to rotate with the shaft 10. These weights engage beneath curved extensions 24 of a sleeve 26 slidably mounted on the shaft 10, the upper end of this sleeve sliding on a casing 28 fixed on the shaft 10. Within the sleeve 26 and the casing 28 and around the shaft 10 are arranged a heavy coil spring 30 resting at its upper end against casing 28 and a light coil spring 32 resting at its lower end against sleeve 26, these springs being separated by a shoulder 34 on a sleeve 36 also slidably on the shaft 10. The length of the spring 30 is such that, when it is fully expanded, the sleeve 26 may be raised for a short distance from its lowest position in which its lower end engages the fixed shoulder 38 on the shaft 10 against the action of the light spring 32 without compressing the spring 30. The light spring is slightly compressed even when the sleeve is in its lowest position.

A horizontal shaft 40 is mounted in the casing 16 and extends through one side thereof. The lower end of the sleeve 26 carries a ball bearing 42, the outer race of which is provided with extending pins 44. Levers 46 are rigidly mounted on the shaft 40 and at their ends are provided with bearing portions 48 engaging the pins 44. It is evident that increase in the speed of the motor will raise the sleeve 26 and thereby rock the shaft 40.

The motor is provided with a fuel pump 50, for supplying fuel thereto. This pump is of any well known type, preferably one in which the amount of feed is controlled by variations in the duration of the fuel feeding period. A timing device 52 is also connected to the pump, this device controlling the time during the cycle of operation of the engine when the feeding action begins. This type of timer is well known. The amount of fuel fed by the pump is controlled by a slidable rod 54, the feed increasing as the rod is moved to the right (Fig. 1). The timing is controlled by a lever 56 mounted on a shaft 58, the time of

injection being earlier as the lever is moved clockwise (Fig. 1). Normally, the rod 54 is controlled by an accelerator pedal 60 slideable in the floor board 62 and normally urged away from the floor board by a spring 64. The accelerator rod 66 is pivoted at 68 to a lever 70 fixed on the shaft 72. A second lever 74 is pivoted on the shaft 72 and is connected by a pivoted link 76 to the rod 54. The upper end of lever 74 has bifurcated portions 78 which carry screws 80 engaging either side of a lug 82 on the lever 70. The angle between levers 70 and 74 can thus be adjusted. It will be clear that depression of the pedal 60 will increase the feed of fuel from the pump.

15 Outside of the casing 16 a triangular lever 84 is rigidly fixed at one apex on the shaft 40. Another apex of this triangle carries a cam surface 86 having two high portions 88, 90 joined by a concave surface 92. At the other apex of the lever 84 is a small cam surface 94. A curved lever 96 having two arms is rigidly fixed on the shaft 72 and carries at the end of its arms rollers 98, 100, the roller 98 engaging the cam surface 86 while the roller 100 lies in the path of the cam surface 94. Adjacent the cam surface 94 the lever 84 has a further cam surface 102 which engages a roller 104 on the lever 56.

20 The cam surface 86 and the lever 84 are so arranged that, when the governor is in its lowest position and the lever 84 is raised, that is, when the engine is stationary, the cam surface 90 will engage or be opposite the roller 98. As the lever is lowered, or moved clockwise, the cam surfaces 92, 88 will come opposite the roller 98. 25 When the speed of the engine is very low, the lever is raised and the cam 94 will engage the roller 100. The cam 102 is so shaped that, as the lever 84 is depressed, the lever 56 is moved further in a clockwise direction against the action of a spring (not shown).

30 The operation of the governing device is as follows:

35 When the motor or engine is not running the sleeve 26 is fully depressed and the lever 84 is in raised position, with the high point 90 opposite the roller 98 and the cam 94 is slightly above the point at which it engages the roller 100. As the engine is set in motion, the governor weights 20 move outward by centrifugal force and raise the sleeve 26. At low speeds, only the light spring 32 resists upward movement of the sleeve 26, since this spring must be almost fully compressed before any resistance is offered by the fully expanded spring 30. Above idling speeds, the spacing sleeve 36 transmits the pressure of the sleeve 26 directly to the heavy spring 30. This makes the governor more sensitive at low speeds, particularly within the idling range. When the engine reaches normal idling speed, the cam 94 is slightly below the roller 100 and the roller 98 is opposite a point on the cam 86 intermediate the high point 90 and the low point of the concave surface 92. If during idling the speed of the engine falls so low that it is likely to stop, the cam 65 94 will move upward and strike the roller 100 which will immediately move the lever 96 and shaft 72 and increase the flow of fuel to the engine. As soon as idling speed is reached, the cam 94 disengages roller 100 and the normal feed 70 for idling is resumed.

75 The purpose of the cam 86 is to limit the feed of fuel to the engine. It is well known that at any given speed an engine will only consume a certain quantity of fuel without smoking. However, as the speed increases, the amount of fuel

which will be burned cleanly also increases. At low speeds, the high surface 90 limits the distance through which the accelerator pedal can be depressed and thereby limits the amount of fuel which can be fed to the amount which the engine can burn without smoking at such a low speed. As the speed increases and the engine is therefore able to burn larger quantities of fuel without smoking, the cam 86 moves to present its concave portion 92 to the roller 98, so that at higher speeds larger quantities of fuel can be supplied. Thus, the governing device at all times prevents the supply of a greater quantity of fuel than can be burned by the engine at the momentary speed thereof. When the speed becomes too great, the high portion 88 reduces the possible fuel feed and thereby acts to slow the engine down to permissible speed.

80 As the engine speed increases, the cam 102 moves downward and rocks the arm 56 to change the timing, preferably advancing the timer at higher speeds.

85 In the form shown in Fig. 3, the governor is similar to that shown in Fig. 2, the shaft 40 being turned in a clockwise direction as the engine speed increases. The fuel pump 50, timer 52 and floor board 62 are also similar to those shown in Fig. 1, although the fuel pump and timer are located higher and above the accelerator rod 66. The shaft 72 carries levers 70 and 105 74 relatively adjustable, the lever 74 being linked to the pump control rod 54.

90 Instead of the lever 84, a lever 110 is rigidly mounted on the shaft 40. This lever has an opening 112 near its outer end, the edges of this opening forming cam surfaces. The edge away from the shaft 40 is a concave curve, having high points 114, 116 and a low portion 118 corresponding to the cam sections 88, 90 and 92 of Fig. 1. In other words, the radius of the portion 118 115 around shaft 40 is greater than the radii of portions 114, 116, although all three of these portions are shaped to form a smooth curve of greatest radius at its center and of gradually decreasing radius towards each end. A lever 120 120 is rigidly mounted on the shaft 72 and carries a roller 122 within the opening 112 and engaging the cam surfaces.

110 The opposite edge of the opening has a sloping cam surface 124 which is shaped to move the 125 lever 120 clockwise as the lever 110 moves counter-clockwise. The lever 110 is also provided with a projection 126. A link 128 is pivoted to the projection 126 and to the arm 130 of the timing mechanism.

130 It will be noted that in this form of the invention the parts are so located that inward movement of the accelerator pedal moves the fuel pump control lever clockwise. The shape of the cam curve controlling this lever is therefore reversed as compared to Fig. 1. By providing the idling cam surface within the opening 112, only a single arm is necessary instead of the double arm lever 96 of Fig. 1.

135 The operation of this form of the invention is, in substance, the same as in the form shown in Fig. 1. As the shaft 40 turns, the cam surfaces 114, 116, 118 first permit the feed of increasing amounts of fuel to the engine and then act to cut down the fuel supply to prevent overspeed. 140 If the speed falls too low, the cam surface 124 strikes the roller 122, and turns the lever 120 to feed more fuel. The timing is clearly varied by the link 128 and is set earlier as the speed increases.

It is evident that by the above construction a single governor acts to regulate the timing, to limit the feed of fuel, to prevent stalling and to avoid undesirably high speeds. The arrangement is simple, inexpensive, compact and sturdy and requires no special skill for operation.

While I have described my invention as applied to an internal combustion engine to which hydrocarbon fuel is fed by a fuel pump, it can obviously be used with any type of motor to which varying quantities of motive fluid are fed. It is likewise evident that, instead of varying the end of the injection period by the accelerator mechanism, the beginning of the period might be controlled jointly by the accelerator and timer to vary the fuel quantity.

While I have described herein some embodiments of my invention, I wish it to be understood that I do not intend to limit myself thereby except within the scope of the appended claims.

I claim:

1. A controlling device for engines, comprising means to supply fuel to the engine, manually operable means to control said fuel supply means, means to limit the movement of said control means, and means controlled by the speed of the engine to vary the position of said limiting means, said limiting means including a cam having two high surfaces and a low surface intermediate said high surfaces, and a member connected to said control means engaging said cam, whereby to prevent the supply of fuel to the engine at too high a rate and to limit the speed of the engine.

2. A controlling device for engines, comprising a governor, a lever controlled by said governor, means for supplying fuel to said engine, and means on said lever to limit the movement of said supply means at low and high speeds while permitting greater movement at intermediate speeds.

3. A controlling device for engines comprising a member having an opening therein, the edges of said opening having cam surfaces thereon, means controlled by the speed of the engine for moving said member, a fuel supply means, manually operable means for controlling said supply means including an element adapted to engage said cam surfaces, said cam surfaces limiting movement of said manually operable means, the limiting action being varied by variations in the speed of the engine, said opening having another edge formed as a cam surface adapted to move said cam engaging element to increase the feed of fuel when the speed of the engine drops below a predetermined point.

4. A controlling device for engines, comprising means to feed fuel to the engine, manually operable means to control said feeding means, means to limit the movement of said control means in a direction to increase the feed of fuel, and means controlled by the speed of the engine to move said limiting means in a direction to permit greater

movement of said control means in a direction to increase the feed of fuel as the speed of the engine increases.

5. A controlling device for engines, comprising means to feed fuel to the engine, manually operable means to control said fuel feeding means, an element, means for moving said element in accordance with the speed of the engine, said control means including a member movable into engagement with said element in a direction substantially perpendicular to the direction of movement of the element, said element limiting movement of said control means in a direction to increase the feed of fuel.

6. A controlling device for engines, comprising means to feed fuel to the engine, manually operable means to control said feeding means, a member having a cam surface thereon, an element connected to said control means engaging said cam surface when said control means is moved in a direction to increase the feed of fuel, said cam surface including a low portion and a higher portion, and means controlled by the speed of the engine to move said member so that said element engages said high portion at low speed and said low portion at a higher speed, whereby as the speed increases said cam surface permits the feeding of a greater quantity of fuel, said cam surfaces limiting the quantity of fuel to the amount the engine can burn at the momentary speed thereof.

7. A fuel-feed control mechanism for an internal combustion engine having a variable fuel-feed device, comprising: manually-operable means associated with and controlling the variable fuel-feed device of the engine, check means effective, at low engine speeds, to prevent manipulation of said manually-operable control means to effect high rates of fuel feeding, and automatic means responsive to instant engine speed and associated with said check means, effective, at increased engine speeds, to relax the restrictive action of said check means upon said manually-operable control means and permit feeding of fuel at an increased rate at increased engine speeds.

8. A fuel-feed control mechanism for an internal combustion engine having a variable fuel-feed device, comprising, manually-operable means associated with and controlling the variable fuel-feed device of the engine, check means effective, at low engine speeds, to prevent manipulation of said manually-operable control means to effect high rates of fuel feeding, and automatic means responsive to instant engine speed and associated with said check means, progressively effective, at increased engine speeds, to relax the restrictive action of said check means upon said manually-operable control means and permit feeding of fuel at a progressively greater rate at increasing engine speeds.

JULIUS KUTTNER.
